SIGNALING SYSTEM

John A. Miller, Louisville, Ky., assignor to
Nashed & United States Signal Co., Incorporated,
Louisville, Ky., a corporation of Kentucky

Application June 25, 1937, Serial No. 150,222
Renewed December 13, 1939

19 Claims. (Cl. 246—114)

My invention relates to a railway signaling system adapted to govern car or train movements on a section of a railway having a plurality of entrances.

5 My invention has particular application to the signaling of a main line haulage of a mine, which usually comprises a section of a railway connected by turnouts leading to the various working sections of the mine.

10 My invention embraces a system of signaling, in which the signal control apparatus for each entrance is entirely symmetrical.

My invention embraces a system that requires but three line wires to connect the apparatus at 15 each entrance.

My invention also embraces a system of signaling in which only one proceed signal is displayed under conditions of either nearly or exactly simultaneous entrance, regardless of the number 20 of vehicles involved in the simultaneous movement.

My invention further resides in the providing of a signaling system in which an "open" in either of the control line wires will produce a 25 failure on the "safe" side, thereby, preventing the establishment of false clear signals in the event a line wire is broken due to falling slate, roof cave-ins, etc.

My invention further resides in a control for 30 a signaling system that is primarily intended for use with those vehicles collecting propulsion current from a trolley wire by trolley wheels or shoes, and in which the control of the signals is governed by trolley contactors engaged by current collectors during their movement on the trolley wire.

My invention still further resides in the arrangement of the signal control circuits, such 35 that the source of current for operating the contactors governing the "proceed" indication is obtained from only one signal station.

It will be further obvious to those skilled in the art that, by reason of the novel arrangement of my signal system, there are many other objects 40 that will become apparent as the specification is read in connection with the accompanying drawing, in which:

Figure 1 is a diagrammatic representation of 45 the circuits and apparatus illustrating one embodiment of my invention.

In Figure 1 the conductor or trolley wire that supplies positive potential to both the signaling system and the vehicles operating on the railway system is indicated by the character T, while, as 50 is well understood in the art, the return conduc-

tor supplying negative potential is either the earth, rails of a railway, or both, as conditions may require.

As hereinbefore expressed, one object of my invention is to provide a signaling system, for 5 a section of railway having a plurality of entries into a main section, in which each entry constitutes a signal station, wherein any desired number of stations may be connected to form a unitarily controlled signal system. Since three 10 stations may be conveniently employed to illustrate the operation of such a signaling system, Fig. 1 diagrammatically illustrates such an embodiment.

In Fig. 1, the section of a railway extending 15 between stations 1 and 3 may be regarded as the main section, while the section of a railway connecting station 2 may be considered a turnout connecting a working section of the mine.

Although the accompanying drawing illus- 20 trates one embodiment of my invention employing a particular form of mechanically actuated trolley contactor, it is to be understood that any other suitable form of contactor, track instrument, or track circuit, may be substituted there- 25 for without departing from the spirit of my invention.

In the embodiment of my invention, each signal station is provided with two vehicle-controlled contact mechanisms, which are adapted 30 to be engaged by the current collector of a moving car to close its corresponding signal control circuit. These vehicle-controlled contact mechanisms may comprise suitable mechanically movable contact members, indicated at station 1 as 35 S₁ and N₁ respectively, that are deflectable in opposite directions by the current collector according to the direction of movement of the car. At station 1, the movable contact member S₁ is provided with a stationary contact 1, which, as 40 indicated by the adjacent arrow, is engaged by the contact member S₁ only when the car enters the signaled section. It will be further noted that the movable contact member N₁ is provided with a stationary contact 70, which, as indicated 45 by the adjacent arrow, is engaged by the contact member N₁ only when the car leaves the signaled section.

The signal indications at each station are dia- 50 grammatically illustrated as signal lamps, how- ever, it is understood that any suitable form of signaling means may be substituted for such signal lamps.

The signal lamps are adapted to convey to the operator of a vehicle the condition of the sig- 55

naled territory, that is, whether same is occupied by moving trains, and the direction in which such trains are moving. It is to be understood that these signal lamps are provided with suitable coloring roundels to distinguish the indications. In the illustrated embodiment of my invention, I employ red roundels for lamps R₁, R₂ and R₃ to denote Stop, and green roundels for lamps G₁, G₂ and G₃ to indicate Proceed. 10 A similar red roundel is provided for signal lamp R.

In Fig. 1 similar relays are employed at each signal station. At station 3 these relays are, namely; a quick-acting neutral relay M₁, a slow release quick pickup neutral relay L₁ and a mechanical interlocking relay A₁—C₁. The mechanical interlocking relay may be of any suitable type in which, for instance, contact arm D₁ remains in one position after the operating coil of relay A₁ has been energized, and remains in another position after the operating coil of relay C₁ has been energized. It is to be noted that the similar relays at each station, together with the other similar apparatuses, are designated by similar characters. For instance, the neutral relay at station 3, corresponding to the neutral relay designated at station 1 as M₁, is designated as M₃.

In the embodiment of my invention, the mechanical interlocking relay is of the type in which the armature D₁ is retained in its operated position by a mechanical latch X₁, and restored to its normal position by the operation of an armature B₁ to release the mechanical latch X₁.

Before proceeding with a detailed description of the operation of my invention, notation will be made of the normal condition of the relays and signals. Normally, with no trains occupying the signaled section, all signals are held at dark, and neutral relays M₁, M₂ and M₃ are retained de-energized, while the neutral relays L₁, L₂ and L₃ are retained energized. Similarly the operating coils of relays C₁, C₂ and C₃ are de-energized at all times excepting when one of the restoring trolley contactors N₁, N₂ or N₃ is being operated by a current collector of a car leaving the signaled section. Also the operating coils of relays A₁, A₂ and A₃ are de-energized at all times excepting when its corresponding trolley contactor S₁, S₂ or S₃ is operated by the current collector of a car entering the signaled section.

Observing the circuits of station 1, it will be noted that the operating coil of relay L₁ is normally energized retaining its armature J₁ in engagement with its front contact 4, thereby normally connecting the operating coil of relay A₁ to the earth or negative return. Thus, as long as the operating coils of the "L" relays are retained energized, the signals are held dark, and the operating coils of the "A" relays are held in condition to be energized in response to an operation of its corresponding trolley contactor. 65 However, when the operating coils of the "L" relays are de-energized, the operating coils of the "A" relays are withheld from energization, and a circuit is completed at each signal station to one or other of the respective signal lamps, dependent upon the selection determined by the respective "M" relay. From the foregoing it will be apparent that, regardless of the manner in which the operating coils of the "L" relays are de-energized, whether due to open circuited coils, short circuited coils, faulty ground connections,

broken line wire, etc., the operating coils of the "A" relays will be "locked out", that is, withheld from operation, and a local circuit to the signal lamps at each station completed.

In Fig. 1 it is important to observe that the operating coils of relays L₁, L₂, L₃ each have one terminal directly connected to the negative return and the other terminal connected to a common line wire extending between the three signal stations, which line wire includes wires 26 and 29. Thus, at station 3, wire 25 connects one terminal of the operating coil of relay L₃ to the negative return, while wire 24a connects the other terminal thereof to line wire 26. Similarly, at station 1, wire 28 connects one terminal of the operating coil of relay L₁ to the negative return, while wire 27 connects the other terminal thereof to line wire 29. Likewise, at station 2, wire 30 connects one terminal of the operating coil of relay L₂ to the negative return, while the other terminal of the coil of relay L₂ is connected to line wire 29. Obviously, line wire 29 is an extension of line wire 26, therefore these permanently connected wires will hereinafter be referred to as the first line wire 26—29. Accordingly, whenever the first line wire 26—29 is at positive potential, the operating coils of relays L₁, L₂ and L₃ are energized.

Similarly, each of the operating coils of relays C₁, C₂ and C₃ have one terminal directly connected to the negative return and the other terminal connected to a restoring line wire extending between the three stations, which restoring line wire includes wires 63 and 66. Thus, at station 3, wire 61 connects one terminal of the operating coil of relay C₁ to the negative return while wire 71 connects the other terminal thereof to line wire 62. Similarly, at station 1, wire 65 connects one terminal of the operating coil of relay C₁ to the negative return, while wire 64 connects the other terminal thereof to line wire 63. Likewise, at station 2, wire 67 connects one terminal of the operating coil of relay C₂ to the negative return, while the other terminal thereof is connected to line wire 66. Obviously, line wire 66 is an extension of line wire 63, therefore these permanently connected wires will hereinafter be referred to as the restoring line wire 63—66. Accordingly, whenever the restoring line wire 63—66 is at positive potential, the operating coils of relays C₁, C₂ and C₃ are energized.

To provide for the placing of the restoring line wire 63—66 at positive potential, a normally open contact of each restoring trolley contactor is connected thereto. Thus, at station 3, contact 71 is connected to the restoring line wire 63—66. Similarly, at station 1, the contact 70 is connected to the restoring line wire 63—66, and, at station 2, contact 69 is connected to the restoring line wire 63—66.

As hereinbefore described, each of the aforesaid contacts 69, 70 and 71 are electrically connected to the positive conductor T, when the movable element of the corresponding restoring contactor is engaged by a trolley wheel leaving the signaled section.

To provide for the placing of the first line wire 26—29 at positive potential, a series line circuit is provided between stations 1, 2 and 3, which line circuit includes a normally closed switch on 70 the "A" relays of each station. In the illustrated embodiment, this series line circuit begins at station 1 with wire 8, which wire connects the armature D₁ of relay A₁ to the positive conductor T. From the normally engaged back contact 19 of 75

armature D₁, the line circuit continues via wire 20, which wire connects the contact 19 to armature D₂ of relay A₂ at station 2. From station 2, the line circuit continues via wire 22, which 5 wire connects the normally engaged back contact 21 of armature D₂ to the armature D₃ at station 3. At the last station the series line circuit is connected, via the normally closed switch of the corresponding "A" relay and a jumper wire, to 10 the first line wire. Thus, at station 3, which is the last station in the illustration, the normally engaged back contact 23 of armature D₃ is connected by the jumper wire 24 to the first line wire 26-29. Obviously, as long as each of the normally closed switches D₁-19, D₂-21 and D₃-23 15 remain closed, the first line wire 26-29 is retained at positive potential, and each of the operating coils of relays L₁, L₂ and L₃ are energized. Thus, the invention embraces a system in which 20 the operating coils of the restoring relays are permanently connected in multiple, and temporarily electrically connected to a source of current via a circuit including a normally open contact, which contact is temporarily closed as the train leaves 25 the signaled section.

The invention further embraces a system in which the operating coils of the signal controlling relays are likewise permanently connected in multiple and normally electrically connected to a source of current via a series line circuit including a normally closed switch at each station, which retains the signal controlling relays normally energized. Having thus enumerated the 30 essential features of my invention, I will now describe their operation, and the manner in which they are structurally embodied in a signaling system.

Vehicle operation

With no car or train in the signaled section, 40 all signals are held in a normally dark condition. The control effecting this condition of the signals, includes the series line circuit, which retains the operating coils of the "L" relays energized. In Fig. 1, this series line circuit is completed from the positive conductor T at station 1, through wire 6, armature D₁, contact 19, wire 20, armature D₂, contact 21, wire 22, armature 45 D₃, contact 23, jumper wire 24, wire 24a, operating coil of relay L₃, wire 25 to the negative return. It will also be observed that the operating coil of relay L₁ is likewise connected to positive potential from jumper wire 24, through wires 26 50 and 27; the operating coil of relay L₁ being connected to the negative return through wire 28. The operating coil of relay L₂ is likewise connected to positive potential from the jumper wire 24 through wires 26 and 29; the operating coil of relay L₂ being connected to the negative return through wire 30. The latter mentioned circuits from jumper wire 24, to each of the operating coils of the "L" relays, merely connects each of the operating coils in a multiple circuit; the 55 jumper wire 24 serving to supply positive potential obtained from station 1 through a series line circuit that includes an armature and back contact of the "A" relays at each signal station.

With further reference to Fig. 1 it will be noted 70 that the "N" restoring contactors are each electrically connected to the restoring line wire 63-66, and that the operating coils of the "C" relays at each signal station are connected to the 75 restoring line wire for energization whenever one

of the restoring contactors is operated by a car leaving the signaled section.

Assuming that a vehicle enters at station 1, the engagement of its current collector with its restoring contactor N₁ will have no effect on the 5 operation of the system. However, when the trolley wheel of the entering vehicle engages the setting contactor S₁, a circuit is completed from the trolley conductor T through contact 1, wire 2, operating coil of relay A₁, wire 3, contact 4, 10 armature J₁, wire 5 to the negative return. This energization of the operating coil of relay A₁ will cause the armature D₁ to disengage its back contact 19, and engage its front contact 7. This disengagement of back contact 19 opens the series 15 line circuit including wires 6, 20, 22 and 24, which normally retains the first line wire 26-29 at positive potential, thereby de-energizing the operating coils of the "L" relays at each respective signal station. The de-energization of the operating coils of the "L" relays will cause their respective armatures to release from their operated 20 positions. When the armature J₁ of relay L₁ is released, the circuit of the operating coil of relay A₁ is opened by the disengagement of contact 4, and the G₁ signal lamp circuit is connected to the negative return through back contact 11 armature J₁ and wire 5.

When the armature D₁ of relay A₁ was operated the mechanical latch X₁ moved into the path of the armature and mechanically retained same in its operated position. In its operated position the armature D₁ engaged front contact 7 and completed a circuit for energizing the operating coil of relay M₁, the latter circuit being completed from the positive conductor T, through wire 6, armature D₁, contact 7, wire 8, operating coil of relay M₁, wire 9 to the negative return. This energization of the operating coil of relay M₁ will cause armature H₁ to disengage back 30 contact 13 and to engage front contact 15. Therefore, the circuit of the proceed signal lamp G₁ is completed from the positive conductor T, through wire 18, signal lamp G₁, wire 16, contact 15, armature H₁, wire 12, contact 11, armature J₁, 35 wire 5 to the negative return. The opening of the series line circuit through the operation of armature D₁, also de-energized the operating coil L₂ at station 2, thereby causing its armature J₂ to disengage its front contact and to engage its back contact 11a. Inasmuch as the operating coil of relay M₂ at station 2 is not energized, the 40 circuit of the stop signal R₂ is completed from the positive conductor T, through wire 17a, signal lamp R₂, wire 14a, contact 13a, armature H₂, 45 wire 12a, contact 11a, armature J₂, wire 5a to the negative return. Similarly the releasing of armature J₃ at station 3 completed the circuit of the stop signal R₃ from the positive conductor T, through wire 17b, signal lamp R₃, wire 14b, contact 13b, armature H₃, wire 12b, contact 11b, armature J₃, wire 5b to the negative return. It is important to note that the release of armatures J₂ and J₃ at stations 2 and 3, respectively, disconnected the operating coils of relays A₂ and 50 A₃ from the negative return, thereby preventing the energization of these operating coils should a car attempt to enter the signaled section at stations 2 and 3 with the stop signals R₂ and R₃ 55 displaying.

The car entering at station 1, and occupying the signaled section, may leave at any one of the stations and restore the system to normal. It will be assumed that the car leaves the signaled section at station 3. Therefore, when the cur- 70 75

rent collector of the car engages the contactor S3, no change in the controls will be effected. However, when the current collector engages the contactor N3, the contact 71 is connected to trolley or 5 positive conductor T, thereby placing positive potential on the restoring line wire including wires 63 and 66. As previously mentioned, each of the operating coils of the relays C1, C2 and C3 are permanently connected to the restoring line 10 wire. Therefore, placing the restoring line wire at positive potential will cause the operating coils of the relays C1, C2 and C3 to be momentarily energized. The operation of armatures B2 and B3 of relays C2 and C3 operates their respective 15 mechanical latches X2 and X3, but since armatures D2 and D3 were not previously operated, no further operation of these relays is made. At station 1, however, the operation of the armature D1 operates the mechanical latch X1 and moves same 20 out of the path of armature D1, thereby permitting armature D1 to restore to its normal position.

The resultant restoration of armatures J1, J2 and J3 to their normal positions restores the 25 signal lamps at each station to their normal dark conditions, and connects the operating coil of each respective "A" relay to the negative return so that it may be operated by a car entering the signaled section.

30 In the preceding description it was assumed that a single car entered at station 1. To explain the operation of my invention under simultaneous entrance, it will be assumed that a car enters at station 2 simultaneous with the car at 35 station 1. Under this condition of operation, the operating coils of relays A1 and A2 are simultaneously energized. The simultaneous operation of armatures D1 and D2 opens the series line circuit at both stations 1 and 2, and thereby de- 40 energizes the operating coils of relays L1, L2 and L3. Inasmuch as armatures D1 and D2 were simultaneously operated, the mechanical latches X1 and X2 retain their respective armatures in 45 their operated positions.

45 Referring particularly to the circuits of station 1, it will be noted that the operation of armature D1 removed positive potential from armature D2 of station 2, and completed the circuit for the energization of the operating coil of relay M1, thereby permitting energization of the proceed signal G1 in the same manner as described in connection with a single car entering at station 1. Similarly, the stop signal R3 at 50 station 3 is displayed. Thus with cars entering simultaneously at stations 1 and 2, only the car approaching at station 1 receives the proceed signal.

55 I will now assume that the car at station 2 operated the setting contactor S2 slightly before the car at station 1 operated its setting contactor S1. Under this condition of operation it will be apparent that the operating coil of relay A2 is energized before the operating coil of relay A1. It will also be apparent that, if this time is sufficient to permit the armature J1 of relay L1 to disengage its front contact 4 before the operating coil of relay A1 can operate its armature D1, the mechanical latch X2 will retain armature D2 operated while armature D1 will remain in its unoperated position. Thus, the armature D2 being connected to positive potential T via wire 29, contact 19, armature D1 and wire 6, will bring about the energization of the operating coil of relay M2, therefore, the armature H2 will disengage its back contact 13a and engage its front contact 15a

thereby permitting energization of the proceed signal G2. At station 1, however, since the armature D1 was not operated, the operating coil of relay M1 will not be energized. Therefore, the release of armature J1 completes the circuit of 5 the stop signal R1 from the positive conductor T through wire 19, signal lamp R1, wire 14, contact 13, armature H1, wire 12, contact 11, armature J1, wire 5 to the negative return. Inasmuch as no car operated at station 3, the stop signal R3 is displayed as hereinbefore mentioned. 10

From the foregoing it will be apparent that in order for the proceed signal to be displayed at a station remote from the location where the signal control wire is connected to positive potential, 15 it is necessary for the armature of the respective "A" relay to be operated before the armature of the "A" relay nearer the said location. Thus, according to Fig. 1, under simultaneous operation of armatures D1, D2 and D3, station 1 receives the 20 proceed signal. With simultaneous operation of armatures D2 and D3 station 2 receives the proceed signal. However, under any circumstances if, for instance, armature D3 is operated before armature D1 or D2, the operating coil of relay 25 M3 is energized, which permits the proceed signal G3 to be displayed at station 3. Thus, the signal control circuits are arranged to permit but one proceed signal to be displayed at one time.

As described under the operation of a single car 30 receiving a proceed signal at station 1, under simultaneous operation the car receiving the proceed signal may leave the signaled section at any station, and operate to restore the signals to normal as previously described. Therefore, regardless of whether the restoring contactor N1, N2 or N3 is operated, the relays and signals are restored to normal in the same manner. 35

At station 2 a stop signal R is provided and located to stop a car approaching station 2 before 40 operating the setting or restoring contactors S2 and N2, whenever the signaled section is occupied.

Referring to the circuits of station 2, it will be noted that whenever the armature J2 of relay L2 is released, the circuit of the stop signal is completed from positive potential T, through wire 36, signal lamp R, wire 35, wire 12a, contact 11a, armature J2, wire 5a to the negative return. The purpose of stop signal R is to prevent cars approaching the signaled section from passing its 50 respective setting contactor while the signaled section is occupied, and it is to be understood that a similar stop signal is to be provided at stations 1 and 3 when this feature is required.

55 Referring further to Fig. 1 it will be noted that each of the relays L1, L2 and L3 is provided with a convenient means for slightly retarding the release of their respective armature. The purpose of this arrangement is to assure operating current flowing through the operating coil of 60 the corresponding "A" relay sufficiently long to permit its respective armature to be mechanically latched in its operated position. For instance, at station 1 when the operating coil of relay A1 is energized the armature D1 is operated and instantly de-energizes the operating coil of relay L1. The armature J1 of relay L1 will not immediately release, thereby permitting the operating coil of relay A1 to be energized sufficiently long 65 to assure armature D1 engaging its front contact 1. The armature J1 of relay L1 will not immediately release, thereby permitting the operating coil of relay A1 to be energized sufficiently long 70 to assure armature D1 engaging its front contact 1.

Having thus described my invention, I claim:

1. In a control system comprising similar apparatus at each of a plurality of separate sta- 75

- tions, the apparatus at each station comprising a normally open electric circuit including an electro-magnet, a vehicle-responsive switch for closing the said circuit upon the entry of a car into the block; an armature operated by the said electro-magnet; a second electro-magnet normally energized; an armature normally maintained in its operated position by the said second electro-magnet; means, controlled by the armature of the second mentioned electro-magnet, to render ineffective the said electric circuit when the said second electro-magnet is de-energized; means, controlled by the armature of the first electro-magnet, to de-energize the said second electro-magnet to render the said electric circuit ineffective; signaling means; and means, controlled by the armature of the second mentioned electro-magnet, operating said signaling means when the said second electro-magnet is de-energized.
20. 2. In a control system comprising similar apparatus at each of a plurality of separate stations, the apparatus at each station comprising a normally open electric circuit including an electro-magnet; a vehicle-responsive switch for closing the said circuit upon the entry of a car into the block; an armature operated by the said electro-magnet; a second electro-magnet normally energized; an armature normally maintained in its operated position by the second electro-magnet; a third electro-magnet; means controlled by the said third electro-magnet and operable to retain the first mentioned armature in its operated position; means, controlled by the operation of the first mentioned armature, to de-energize the said second electro-magnet; signaling means; means, controlled by the armature of the second mentioned electro-magnet, operating said signaling means when the said second electro-magnet is de-energized; and means, responsive to a car leaving the block, to energize the said third electro-magnet, to render ineffective the said retaining means, thereby restoring the said armature to its unoperated position when the said retaining means is rendered ineffective, so as to re-energize the said second electro-magnet.
30. 3. In a railway block signaling system comprising similar apparatus at each of a plurality of separate stations, the apparatus at each station comprising a normally open electric circuit including an electro-magnet; an armature for the said electro-magnet; means, actuated upon the entry of a car into the block, for closing the said circuit; a second electro-magnet normally energized; an armature normally maintained in its operated position by the said second electro-magnet; a third electro-magnet; a mechanical latch controlled by the said third electro-magnet, and adapted to retain the armature of the first mentioned electro-magnet in its operated position; a fourth electro-magnet and an armature operated thereby; stop and proceed signals controlled by the last mentioned armature; means, controlled by the operation of the armature of the first mentioned electro-magnet, to de-energize the said second electro-magnet; means, controlled by the said operation of the said first mentioned armature, to energize the said fourth mentioned electro-magnet; means, controlled by the release of the armature of the said second electro-magnet from its operated position, to render the circuit of the first mentioned electro-magnet ineffective to a car entering the block; and means, controlled by the release of the said armature of the said second electro-magnet, to operate the said proceed signal, when the armature of the said fourth mentioned
- electro-magnet is operated; and means, controlled by the said operation of the armature of the said first mentioned electro-magnet, to de-energize the corresponding second electro-magnets at each of the other stations, to operate the said stop signals at each of the said other stations.
4. In a railway block signaling system, as set forth in claim 3, comprising means, controlled by a vehicle leaving the block, to energize the said third electromagnet to remove the mechanical latch from the armature of the first mentioned electro-magnet, and to thereby re-energize the said second electro-magnets at each station to discontinue the operation of the said signals.
5. In a railway block signaling system comprising a normally open electric circuit including an electro-magnet; means, actuated upon the entry of a car into the block, for closing the said circuit; an armature operated by the said electro-magnet; a second electro-magnet; means, controlled by the said second electro-magnet, to retain the said armature in its operated position; a third electro-magnet normally energized; means, controlled by the said armature, to de-energize the said third electro-magnet; a fourth electro-magnet normally de-energized; means, controlled by the said armature, to energize the said fourth electro-magnet; a proceed signal; and means, controlled by the said de-energization of the said third electro-magnet and the said energization of the fourth electro-magnet, to operate the said proceed signal.
6. In a railway block signaling system, as set forth in claim 5, comprising means, responsive to a vehicle leaving the said block, to energize the said second electro-magnet to render ineffective the said retaining means, and to thereby restore the said third and fourth electro-magnets to their normal conditions.
7. In a control system for railway block signaling comprising a normally open circuit circuit including an electro-magnet; means, actuated upon the entry of a car into the block, for closing the said circuit; an armature operated by the said electro-magnet; means operable to retain the said armature in its operated position; a second electro-magnet normally energized; a switch in the said circuit normally maintained closed by the said second electro-magnet; means, controlled by the operation of the said armature, to de-energize the said second electro-magnet to open the said switch; a proceed signal; and means, controlled by the armature of the first mentioned electro-magnet, when the said armature is in its operated position, to operate the said proceed signal.
8. In a control system for railway block signaling, as set forth in claim 7, comprising means, responsive to a vehicle leaving the said block, to discontinue the operation of the said retaining means, and to thereby restore the said armature to its normal position.
9. A railway block signaling system for a plurality of separated stations having, in combination, a source of power; a first line connection extending to each station; a signal controlling relay at each station; a normally energized operating coil for each signal controlling relay, each of the latter operating coils having one terminal connected to the first line connection and the other terminal connected to one terminal of the source of power; a normally closed switch at each station; a second line connection connecting the said first line connection to the

other terminal of the source of power, the said second line connection including the normally closed switch at each station connected in series therewith; control means at each station oper-
5 able to open the corresponding normally closed switch, to disconnect the first line connection from the other terminal of the source of power, and thereby to de-energize each of the operating coils of the said signal controlling relays;
10 means at each station operable to retain the corresponding control means operated; a second relay at each station; a normally de-energized operating coil for each second relay, each of the latter operating coils having one terminal connected to the said one terminal of the source of power; means at each station, actuated by the operation of its corresponding control means, for connecting the other terminal of the operating coil of the corresponding second relay to
15 the said other terminal of the source of power; a normally dark proceed signal at each station; means, controlled by the de-energization of the operating coil of a signal controlling relay and the energization of the operating coil of the
20 corresponding second relay, for operating the corresponding proceed signal; a normally dark stop signal at each station; means controlled by the de-energization of the operating coil of a signal controlling relay and the de-energization of the
25 corresponding second relay, for operating the corresponding proceed signal; a normally dark stop signal at each station; means controlled by the de-energization of the operating coil of a signal controlling relay and the de-energization of the
30 operating coil of the corresponding second relay, for operating the corresponding stop signal; and means, responsive to a car leaving the signal block, for rendering ineffective the said retaining means, thereby to restore the relays and
35 signals to normal conditions.

10. A railway block signaling system for a plurality of separated stations having, in combination, a source of power; a first line connection extending to each station; a signal controlling relay at each station; a normally energized operating coil for each signal controlling relay, each of the latter operating coils having one terminal connected to the first line connection and the other terminal connected to one terminal of the source of power; a normally closed switch at each station; a second line connection connecting the said first line connection to the other terminal of the source of power, the said second line connection including the normally closed switch at each station connected in series therewith; control means at each station operable to open the corresponding normally closed switch, to disconnect the first line connection from the other terminal of the source of power, and thereby to de-energize each of the operating coils of the said signal controlling relays; means at each station operable to retain the corresponding control means operated; signalling means at each station; means, controlled by the de-energization of the said operating coils, for operating the corresponding signalling means; and means responsive to a car leaving the said block, for rendering ineffective the said retaining means, thereby to restore the said operating coils to their normally energized condition.

66 11. A railway block signaling system for a
plurality of separated stations having, in com-
bination, a source of power; a first line connec-
tion extending to each station; a signal con-
trolling relay at each station; a normally ener-
gized operating coil for each signal controlling
70 relay, each of the latter operating coils having
one terminal connected to the first line connec-
tion and the other terminal connected to one
75 terminal of the source of power; a normally

closed switch at each station; a second line connection connecting the said first line connection to the other terminal of the source of power, the said second line connection including the normally closed switch at each station connected in series therewith; control means at each station operable to open the corresponding normally closed switch, to disconnect the first line connection from the other terminal of the source of power, and to thereby de-energize each of the operating coils of the said signal controlling relays; means at each station operable to retain the corresponding control means operated; a second relay at each station; a normally de-energized operating coil for each second relay, each of the latter operating coils having one terminal connected to the said one terminal of the source of power; means at each station, actuated by the operation of its corresponding control means, for connecting the other terminal of the operating coil of the corresponding second relay to the said other terminal of the source of power; means controlled by the opening of one or more of the said switches, providing energization of only one of the operating coils of the said second relays; a normally dark proceed signal at each station; means, controlled by the de-energization of the operating coil of a signal controlling relay and the energization of the operating coil of the corresponding second relay, for operating the corresponding proceed signal; a normally dark stop signal at each station; means controlled by the de-energization of the operating coil of a signal controlling relay and the de-energization of the operating coil of the corresponding second relay, for operating the corresponding stop signal; and means, responsive to a car leaving the signal block, for rendering ineffective the said retaining means, thereby to restore the relays and signals to normal conditions.

12. A railway block signaling system for a plurality of separated stations, having, in combination, a source of power; a signal controlling relay at each station; a normally energized operating coil for each signal controlling relay; a normally closed line circuit including the operating coil of each signal controlling relay and the source of power for retaining the operating coil of each signal controlling relay normally energized; a normally closed switch at each station, each switch included in the said circuit and operable to open the said circuit for de-energizing all of the said operating coils; control means at each station for operating the corresponding switch to open the said circuit; means at each station operable to retain the corresponding control means operated; a second relay at each station; a normally de-energized operating coil for each second relay; a normally open control switch at each station closed by the operation of the corresponding control means; means at each station controlling the closing of each respective normally open switch, for energizing the operating coil of the corresponding second relay; a normally dark proceed signal at each station; means, controlled by the de-energization of the operating coil of a signal controlling relay, and the energization of the operating coil of the corresponding second relay, for operating the corresponding proceed signal; a normally dark stop signal at each station; means, controlled by the de-energization of the operating coil of a signal controlling relay and the de-energization of the operating coil of the corresponding second relay, for operating the corresponding stop signal; and 45 50 55 60 65 70 75

means, responsive to a car leaving the signal block, for rendering ineffective the said retaining means, thereby to restore the relays and signals to normal conditions.

- 5 13. A railway block signaling system for a plurality of separated stations having, in combination, a source of power; a signal controlling relay at each station; a normally energized operating coil for each signal controlling relay; a 10 normally closed line circuit including the operating coil of each signal controlling relay and the source of power for retaining the operating coil of each signal controlling relay normally energized; a normally closed switch at each station, 15 each switch included in the said circuit and operable to open the said circuit for de-energizing all of the said operating coils; signaling means at each station; and means at each station, responsive to the de-energization of the operating 20 coil of the corresponding signal controlling relay, for operating the corresponding signaling means.

14. A railway block signaling system for a plurality of separated signal stations having, in combination, a source of power; a signal controlling relay at each station; a normally energized operating coil for each signal controlling relay; a normally closed line circuit including the operating coil of each signal controlling relay and the source of power for retaining the operating 25 coil of each signal controlling relay normally energized; a normally closed switch at each station, each switch included in the said circuit and operable to open the said circuit for de-energizing all of the said operating coils; a normally 30 de-energized operating coil at each station, which, when energized, operates the corresponding normally closed switch; a second switch at each station normally retained closed by the normally energized operating coil of the corresponding 35 signal controlling relay; a normally open electric circuit at each station including the corresponding normally closed second switch connected in series therewith; means at each station, actuated upon the entry of a car into the 40 signal block at the corresponding station for closing the corresponding normally open circuit; means at each station operating to retain the corresponding first mentioned normally closed switch operated, when the corresponding normally 45 de-energized operating coil is energized; signaling means at each station; means at each station, responsive to the de-energization of the operating coil of the corresponding signal controlling relay, for operating the corresponding 50 signaling means; and means, responsive to a car leaving the said signal block, for rendering ineffective the said retaining means.

15. A railway block signaling system for a plurality of separated stations having, in combination, a source of power; a normally-energized relay at each station, each relay having a normally-energized relay coil; a normally-closed line-circuit including the relay coil at each station and the source of power for retaining the relay coil at each station normally energized; a normally-closed switch at each station included in the said circuit, each switch operable to open the said circuit for de-energizing all of the said relay coils; control means at each station for operating the 60 corresponding switch to open the said circuit; signaling means at each station; and means at each station, operated by the de-energization of the corresponding relay coil, for operating the corresponding signaling means.

75 16. A railway block signaling system for a plu-

rality of separated stations having, in combination, a source of power; a first line connection extending to each station; a normally-energized electro-magnet at each station, each magnet having one terminal connected to the first line connection and its other terminal connected to one terminal of the source of power; a normally closed switch at each station; a second line connection connecting the said first line connection to the other terminal of the source of power, the 10 said second line connection including the normally closed switch at each station connected in series therewith; control means at each station operable to open the corresponding normally closed switch, for disconnecting the first line connection from the said other terminal of the source of power, and thereby to de-energize the electro-magnet at each station; signaling means at each station; and means at each station, operating in response to the de-energization of the corresponding electro-magnet, for displaying the 15 corresponding signaling means.

17. A railway block signaling system for a plurality of separated stations having, in combination, a source of power; a first line connection 25 extending to each station; a normally-energized electro-magnet at each station, each magnet having one terminal connected to the first line connection and its other terminal connected to one terminal of the source of power; a normally 30 closed switch at each station; a second line connection connecting the said first line connection to the other terminal of the source of power, the said second line connection including the normally closed switch at each station connected in series therewith; control means at each station operable to open the corresponding normally 35 closed switch, for disconnecting the first line connection from the said other terminal of the source of power, and thereby to de-energize the electro- 40 magnet at each station; a normally-open switch at each station, closed by the operation of the corresponding control means; a proceed signal at each station; means at each station controlled by the closing of the corresponding normally- 45 open switch, for displaying the corresponding proceed signal; a stop signal at each station; and means at each station, controlled by the de-energization of the corresponding electro-magnet, for 50 displaying the corresponding stop signal.

18. A railway block signaling system for a plurality of separated stations having, in combination, a source of power; a first line connection extending to each station; a normally-energized electro-magnet at each station, each magnet having one terminal connected to the first line connection and its other terminal connected to one terminal of the source of power; a normally closed switch at each station; a second line connection connecting the said first line connection to the other terminal of the source of power, the 60 said second line connection including the normally closed switch at each station connected in series therewith; control means at each station operable to open the corresponding normally 65 closed switch, for disconnecting the first line connection from the said other terminal of the source of power, and thereby to de-energize the electro-magnet at each station; a stop signal at each station; means at each station operating in response to the de-energization of the corresponding electro-magnet, for displaying the corresponding stop signal; a proceed signal at each station; a normally-open switch at each station, closed by the operation of the corresponding con- 70

trol means; means at each station, controlled by the closing of the corresponding normally-open switch, for displaying the corresponding proceed signal; and means controlled by the 5 opening of the said normally-closed switches providing for the display of only one of the said proceed signals, when more than one of the said normally-open switches are closed.

19. A railway block signaling system for a plurality of separated stations, having in combination, a source of power; signaling means at each of said stations; a control relay at each station; means at each station, controlled by the corresponding control relay, for operating the corresponding signal; a normally-closed switch at each station; a first line connection extending to each station; a normally-energized operating-coil for

each control relay, each coil having one terminal connected to the said first line connection and its other terminal connected to one terminal of the said source of power; a second line connection connecting the said first line connection to 5 the other terminal of the said source of power, the said second line connection including the normally-closed switch at each station connected in series therewith; control means at each station operable to open the corresponding normally-closed switch, for opening the said second line connection, and thereby de-energizing each of the operating coils of the said control relays so as to render the control relay at each station effective to control the corresponding signaling 10 means.

JOHN A. MILLER.
